Des. 183,222
Patented July 15, 1958

183,222

SHOWER CAP

Harry Mills, New York, N. Y.

Application October 21, 1957, Serial No. 48,169

Term of patent 14 years

(Cl. D3—13)

Fig. 1.

Fig. 4.

Fig. 2.

Fig. 5.

Fig. 1 is a top plan view of a shower cap, showing my new design;

Fig. 2 is a side elevational view of the shower cap shown in Fig. 1;

Fig. 3 is a bottom plan view;

Fig. 4 is a front elevational view; and

Fig. 5 is a rear elevational view thereof.

I claim:

The ornamental design for a shower cap, substantially as shown.
